STATOR CONSTRUCTION FOR AXIAL-FLOW FLUID MACHINE

Nigel Edward Payne, Burton-on-Trent, and Frederick Freeman, Derby, England, assignors to Rolls-Royce Limited, Derby, England, a British company

Application July 19, 1956, Serial No. 598,909

Claims priority, application Great Britain August 5, 1955

7 Claims. (Cl. 253—78)

This invention relates to axial-flow fluid machines such as turbines or compressors of gas-turbine engines.

This invention has for an object to provide a construction of stator with hollow blades showing advantages in manufacture and operation.

According to the present invention, a stator of an axial-flow fluid machine comprises a ring of hollow stator blades secured at their inner and outer ends in hollow, box-like inner and outer blade platform structures, the passages through the blades opening into the interiors of the box-like platform structures, an outer casing structure wherein the blades are mounted through the outer platform structures, first duct connections connecting the interiors of the outer platform structures to externally of the outer casing structure, and second duct connections connecting the interiors of the inner platform structures to a chamber within internal stationary structure of the engine.

The construction of this invention enables low-pressure air to be passed through the blades, say for cooling, as compared with high-pressure air usually employed hitherto, the air flowing either from a low-pressure chamber internally of the engine to externally of the outer casing structure, or in the reverse direction; a more efficient operation of the fluid machine is thus achieved.

The blades may have individual inner and outer platform structures, but preferably the blades are arranged in a plurality of sets, there being say three blades in a set, and the blades of a set have common inner and outer platform structures which act as manifolds for distributing air to and collecting air from the blades of the set. Such a blade and platform arrangement improves the load-bearing capacity of the structure, and at the same time reduces the number of duct connections and the number of ports necessary in the outer casing structure as compared with constructions in which each blade has individual platform structures.

In one preferred construction, the radially outer walls of the common outer platform structures and the outer casing structure have ports therein formed by hollow bosses, and tubular plugs engage by their ends in the bores to connect the interiors of the outer platform structures to externally of the outer casing structure, and the common inner platform structures have ports to their interiors formed by hollow radial bosses on their radially inner walls to engage plug-wise in radial sockets provided on a wall of the chamber and opening into the chamber. In this case, the socket-engaging bosses may also be employed to locate internal engine structure coaxially within the ring of stator blades.

There will now be described a gas turbine having nozzle guide vanes at the entry of the turbine constructed in accordance with this invention. The description refers to the accompanying drawings in which—

Figure 1 is a part axial section through the turbine,

Figure 2 is a section on the line II—II of Figure 1, 70

Figure 3 is an axial section through a modified construction, and

2

Figure 4 is a section on the line IV—IV of Figure 3.

Referring to the drawings, the turbine comprises a rotor having a shaft 10 which has secured to one end thereof a turbine disc 11 with a ring of rotor blades 12 mounted on its periphery. The turbine also comprises a stator having an outer load-bearing casing structure 13 from which is supported a ring of nozzle guide vanes 14 through the passages between which hot gas from combustion equipment 15 flows to be directed onto the rotor blades 12, and the nozzle guide vanes 14 in turn support a bearing 16 for the downstream end of the turbine shaft 10.

The nozzle guide vanes 14 which are hollow are arranged in sets of three (see Figure 2) and each set of three nozzle guide vanes 14 has associated with it a hollow, box-like inner platform structure and a hollow box-like outer platform structure.

The outer platform structure of each set of vanes comprises a plate 17 having slots in which the outer ends of the vanes are secured as by welding or brazing and the plate 17 forms a portion of the wall of the working fluid annulus of the turbine. The plate 17 is secured to flanges 18a around the edges of an outer wall part 18 so that the plate 17 is in spaced relation to the outer wall part 18 and so that a manifold space 19 is formed into which open the outer ends of the passages through the vanes 14. The outer wall part 18 of the outer platform structure has formed integrally with it a hollow boss 20, the bore of which opens into the manifold space 19 and forms a socket to receive one end of a tubular plug 21, the opposite end of which is engaged in a socket formed by a hollow boss 22 provided on the outer casing structure 13 and forming a port opening through the outer casing structure to atmosphere. A cross pin 23 is fitted in the boss 22 to prevent the disengagement of the plug 21. The plug 21 has part-spherical end portions by which it engages the bores of the hollow bosses 20 and 22.

The outer wall part 18 is also provided externally with 40 outwardly-extending dogs 24 at axially-spaced points to co-operate with corresponding dogs 25 on the outer casing structure 13 so as to locate the outer platform structure circumferentially in the turbine. The outer wall part 18 is also provided with a thickened edge 26 at its downstream end, which edge is provided with an axially-facing groove to receive the upstream edge of a shroud ring 27 for the turbine rotor blades 12. The shroud ring 27 is located both axially and circumferentially with respect to the outer casing structure 13. Since the gas loads on the vanes 14 tend to displace the vanes downstream, the shroud ring 27 also serves to locate the vanes axially.

The inner platform structure associated with a set of vanes comprises a plate 28 which has an inward flange at its upstream edge and also is formed with slots in which the inner ends of the vanes 14 are secured as by welding or brazing. The plate 28 forms a portion of the inner wall of the working fluid annulus of the turbine. The inner platform structure also comprises an inner wall part 29 having flanges 29a along its circumferentially spaced edges and its downstream edges and the plate 28 is secured to the flanges 29a, so that the plate 28 is spaced from the wall 29 and forms a manifold space 30 into which open the inner ends of the passages in the vanes 14.

The inner wall part 29 has formed integrally with it a hollow boss 31 which forms the plug of a plug and socket duct connection between the manifold space 30 of the inner platform structure and an annular chamber 47 formed in a support for the bearing 16.

The bearing support comprises an upstream radially-extending annular diaphragm 32, a downstream radially-extending annular diaphragm 33 and an annular rim

member 34. The rim member 34 is formed with a number of hollow bosses 35 which form the sockets to receive the plugs 31 and it is also formed with a number of swellings 36 the purpose of which will appear below.

The diaphragms 32, 33 at their outer peripheries lie against the upstream and downstream faces of the rim member 34 and are held in position by upstream and downstream clamping rings 37, 38 and by bolts which pass through the clamping rings, the peripheries of the diaphragms 32, 33 and the swellings 36 of the rim member 34.

At an inner radius the diaphragms 32, 33 are provided with axial flanges 39, 40 which abut one another and hold the diaphragms 32, 33 in axially-spaced relation at this radius. The diaphragm 32 is also provided internally with a radially-inwardly-extending flange 41 having at its free edge a splined axial extension 42 which receives the splined outer race 16a of the bearing 16.

The clamping rings 37, 38 not only serve to hold the diaphragms 32, 33 against the rim member 34 but also serve to locate the inner ends of the nozzle guide vanes 14 with respect to one another and for this purpose the clamping ring 37 is provided with a flange portion 43 with an axially-facing annular slot to receive axial projections 44 at the upstream edges of the inner wall parts 28 and the clamping ring 38 is provided with an axial flange 45 having therein an axially-facing annular slot to receive projections 46 from the downstream edges of the inner wall parts 29.

The annular chamber 47 is bounded by the diaphragms 32, 33, flanges 39, 40 and the rim member 34, and the chamber is used as a collector manifold for low-pressure air to be conveyed through the hollow nozzle guide vanes 14 to atmosphere. The air may be low-pressure air which leaks into space 50 adjacent the compressor, say through a compressor rotor seal, and this air may pass into the chamber 47 through holes 51 in the diaphragm 32. Alternatively or in addition, the air may be low-pressure cooling air tapped-off from a low-pressure stage of the engine compressor and conveyed through the shaft 10 to flow through ports 52 therein adjacent bearing 16 into space 53 and thence through rotating seal 55 which acts as a flow restrictor to space 56. The air then flows through ports 54 in flange 40 from space 56 to the chamber 47. The air flows outwardly from the annular chamber 47 through the ducts formed by the hollow bosses 35 and the hollow plugs 31 into the manifold spaces 30 in the inner platform structures, and then flows outwardly through the hollow nozzle guide vanes 14 into the manifold spaces 19 of the outer platform structures and from thence to atmosphere through ducts afforded by the tubular plugs 21.

Since the air is low-pressure air, the mass flow of air is less than when the air is high-pressure air, and consequently the engine operates more efficiently because less energy is absorbed in the engine in compressing the air specifically tapped for cooling or because the cooling air is leakage air.

It will be noted also that the vanes 14 and their platform structures are of simple construction yet are capable of withstanding heavy loads. Also, the vane structure assists through the bosses 31, 35 in centralising the bearing 16.

In another arrangement (Figures 3 and 4), instead of each set of vanes 14 having associated with it a single box-like outer platform structure, each vane 14 of the set has an individual box-like outer platform structure.

Thus the outer platform structure associated with a set of vanes comprises three plates 117 allocated to respective vanes 14 and having the outer ends of the vanes welded or brazed in slots in them, and corresponding outer wall parts 118 with edge flanges 118a to which the plates 117 are secured. Each plate 117 and its associated outer wall part 118 thus defines a space 119 into which

opens the outer end of the passage through the associated blade.

The parts 118 are formed each with a hollow boss 120 wherein is engaged one end of a tubular plug 121, the opposite end being engaged in a corresponding hollow boss 122 on the outer casing structure 13.

The parts 118 also have outwardly extending ribs 124 which form dogs to engage between corresponding dogs 125 on the casing structure 13 to locate the outer platform structure in position.

We claim:

1. An axial-flow fluid machine comprising a stator casing, an annular structure coaxially within the casing and defining an annular chamber, said structure having an outer annular part radially spaced from the stator casing, a ring of stator blades extending radially between said annular structure and said stator casing, each of said stator blades having a passage extending through it and opening through each end of the blade, means connecting the stator blades with the annular structure, said means comprising a series of part-annular inner hollow structures between the inner ends of the blades and said annular structure, each of said part-annular inner hollow structures subtending at the axis of the machine an angle equal to the angle subtended at the axis by a plurality of said stator blades, each of said part-annular inner hollow structures having radially-spaced inner and outer walls, the outer wall having in it a number of slots equal in number to said plurality of the stator blades and each 20 of said slots having the inner end of a corresponding one of the plurality of stator blades rigidly secured therein whereby the passages in said plurality of the stator blades open to the space between said inner and outer walls, each of said inner hollow structures having a single duct connection extending radially-inwardly from its inner wall to the outer annular part and connecting said space between the inner and outer walls of the inner hollow structure and the annular chamber, and said series 25 of inner hollow structures together defining a complete annulus, and means connecting the stator blades with the stator casing, said means comprising a second series of outer hollow structures which together form a complete annulus radially between the stator casing and the radially-outer ends of the ring of blades, each of said outer hollow structures comprising radially-spaced inner and outer walls, the inner walls of the outer hollow structures having blade-receiving slots therein, the radially-outer ends of the stator blades being rigidly secured in said slots whereby the outer ends of the passages 30 in the stator blades open into the spaces between the walls of the outer hollow structures, a plurality of angularly-spaced pressure fluid connections externally of said stator casing, the number of said pressure fluid connections being equal to the number of outer hollow structures, and a single duct connection extending radially 35 outwardly from the outer wall of each of said outer hollow structures to a corresponding one of said pressure fluid connections.

2. An axial-flow fluid machine according to claim 1, wherein the number of said outer hollow structures is equal to the number of said inner hollow structures, the inner wall of each outer hollow structure has therein a number of blade-receiving slots equal to the number of blades in said plurality of the stator blades, and the blades which are secured in the outer wall of each inner hollow structure, have their outer ends secured in the slots in the inner wall of a corresponding one of the outer hollow structures.

3. An axial-flow fluid machine according to claim 1, wherein the number of said outer hollow structures is equal to the number of blades in said ring of stator blades, the inner wall of each outer hollow structure having a single blade-receiving slot therein.

4. An axial-flow fluid machine according to claim 1, wherein said outer annular part of the annular structure

comprises a number of radially-outwardly-extending sockets equal to the number of inner hollow structures, and the inner wall of each inner hollow structure having formed thereon a hollow radial boss engaging plugwise within a corresponding one of said sockets, the duct connection between the inner hollow structure and the chamber being afforded by said hollow boss and said socket.

5. An axial-flow fluid machine according to claim 1, wherein said annular structure comprises a pair of axially-spaced annular diaphragms, said outer annular part being between said diaphragms adjacent their peripheries and holding them in spaced relation, axial flanges on said diaphragms adjacent their inner peripheries, the axial flanges abutting one another and affording a radially-
inner wall of said annular chamber and clamping means extending through said diaphragms and the outer annular part and holding them in axial abutment, said clamping means also engaging the inner hollow structure and locating them radially with respect to one another.

6. An axial-flow fluid machine according to claim 5, comprising also a rotor, a bearing for the rotor, said

bearing having an outer stationary race, said race being supported by one of said diaphragms at its inner periphery.

7. An axial-flow fluid machine according to claim 1, wherein each of said duct connections extending outwardly from the outer wall of each of said outer hollow structures comprises a hollow boss extending radially outwards from said outer wall, a hollow boss extending outwards from said stator casing, and a tubular plug member having one end engaged in the hollow boss on said outer wall and its opposite end engaging the hollow boss on the stator casing, the tubular plug having its ends part-spherical.
